(57) **CLAIM**

We claim the ornamental design for a multipurpose chair for children, as shown and described above.

DESCRIPTION

FIG. 1 is a top, front and left side perspective view of our new design;

FIG. 2 is a top plan view thereof;

FIG. 3 is a front elevational view thereof;

FIG. 4 is a right side elevational view thereof, the left side being a mirror image;

FIG. 5 is a rear elevational view thereof;

FIG. 6 is a bottom plan view thereof; and,

FIG. 7 is another perspective view thereof, illustrating one mode of use.

The figure shown in broken lines forms no part of the invention claimed.
